MEANS FOR PRODUCING AN EFFECTIVE
SHORT CIRCUIT

Andrew Alford, New York, N. Y., assignor to
Mackay Radio & Telegraph Company, New
York, N. Y., a corporation of Delaware

Application September 27, 1938, Serial No. 231,923

8 Claims. (Cl. 178—44)

My invention relates to high frequency transmission circuits and more particularly to a high frequency network which may be used in connection with a high frequency transmission line 5 to produce the desirable effects obtained by the use of short circuiting bars without the attending disadvantages common to the use of short circuiting bars in these systems.

In the prior art structures for high frequency transmission systems, it has often been found desirable to terminate certain line sections with short circuiting bars. However, such terminations have certain disadvantages due to the fact that a short circuiting bar will not operate as a 10 complete short circuit at these high frequencies and as a result considerable voltage is bound to exist in conductors extended beyond these short circuiting bars.

In accordance with my invention these difficulties are substantially eliminated by substituting a form of network comprising cross connections between the conductors of a transmission line in place of the ordinary short circuiting bar. By the use of such a network the voltage in the 15 conductors beyond the network may be reduced to a substantially negligible value or entirely eliminated.

It is an object of my invention to provide a network which will produce the advantages of 20 a direct short circuiting bar without the attending disadvantages thereof.

It is a further object of my invention to provide high frequency circuits utilizing the network in accordance with my invention.

35 It is a further object of my invention to provide a so-called metallic insulator circuit utilizing networks in accordance with my invention in place of short circuiting bars.

Other objects, advantages and uses of my invention will be apparent from a reading of the 40 particular description of my invention made in connection with the accompanying drawings, in which

Fig. 1 is a diagrammatic showing illustrating 45 the problem which is overcome by the networks in accordance with my invention;

Fig. 2 is an illustration of a network in accordance with my invention;

Fig. 3 illustrates a preferred form of my invention designed to very accurately produce the 50 substantial effect of a short circuiting arrangement;

Figs. 4 and 5 are top and side views respectively, of the network as shown in Fig. 3;

55 Fig. 6 is a diagram of a transmission line pro-

vided with a network in accordance with my invention, for the purpose of explaining the effect of the network;

Fig. 7 illustrates an adaptation of my invention to the construction of so-called metallic insulators;

Fig. 8 illustrates the application of my invention to a conjugate network arrangement;

Fig. 9 illustrates an application of my invention to the tuning of a parasitic reflector; and 10

Fig. 10 illustrates an application of my invention for use in connection with discriminating networks utilizing coupled sections.

In Fig. 1, 11 represents a high frequency transmission line across which is bridged a short 15 section of transmission line 12, terminated at a suitable distance from the transmission line by a short circuiting bar 13. Below the short circuiting bar conductors 12 are extended, as shown at 14. If the energy transmitted over 20 transmission line is of a frequency of, for example, about seventeen megacycles, and it is found possible to light a 220 volt lamp such as indicated at 15 by connecting it across the conductors extended beyond the short; the spacing 25 between the conductors being approximately 12" and the current through the short circuiting bar is in the order of ten amperes. In practice these voltages are often higher than 220 volts 30 because the currents in such short circuiting bars are frequently more than ten amperes.

The practical difficulties to which voltages penetrating beyond these bar shorts are likely to lead, are quite varied and numerous. For example, in the case of a conjugate section arrangement similar to that illustrated in Fig. 8 of the drawings, in which short circuiting bars are used, two principal types of difficulties arise. These types are, one, the impedance of the section is not altogether independent of the length 35 of the wires which extend beyond the bar shorts and consequently the tuning is affected by what may be done to these wires after the position of the short circuiting bar has been properly adjusted. If the wires beyond the shorts are 40 grounded at two different points, as is often convenient from a practical point of view to keep the sections from twisting, then there is introduced a loss of power due to circulation of current in ground. Similarly other difficulties arise 45 in the various systems using a short circuiting bar due to the effect of current penetrating past the short circuiting bar and extending into the conductors.

These various difficulties and inconveniences 55

which arise with the ordinary shorts are obviated by use of a network in accordance with my invention. This network is in reality no short circuit at all in the usual sense of the word, but is a simple network which prevents waves from passing to points beyond it. However, for convenience in referring to the network, I refer to it as an "X type short." It can be shown that if a network is inserted between two spaced points 10 in a transmission line and the line was continued from the junction of these spaced points, that a complete stopping of high frequency energy along the transmission line may be accomplished by making the two arms of the network of such 15 length that their difference is equal to 180 electrical degrees. Bearing this fact in mind, the construction and explanation of the so-called X type shorts will be given with reference to Fig. 2 of the drawings.

20 In this figure 212 represents a high frequency transmission line which may be a line section such as that shown at 12 in Fig. 1. The network in its simplest form may consist of two diagonal wires 23, 24, connected across line 212 in such 25 a way as to cross and form an X. These wires are arranged so as not to make electrical contact at their intersection and may be kept apart by any suitable means such as an insulating spreader similar to 35 shown in Fig. 3. The length of 30 the wires 23, 24, should be generally equal to several times the spacing of the conductors of transmission line 212 and these wires 23, 24, should be of equal length.

The operation of this network may be understood if it is considered as a network in which 35 the line is made to reenter upon itself with a 180° phase shift. Thus the section of transmission line 212 between the points of connection 26, 27, may be considered as one limb A of the 40 network and the conductors 23, 24, as the other limb B of the network. The electrical length of the limb A comprising the line conductors is equal to the distance between 26, 27, in electrical degrees. The electrical length of limb B comprising the conductors 23, 24, is equal to the 45 length of these two conductors in electrical degrees + 180°, because of the transposition at the point of crossing. The electrical perimeter of this network is equal to $U = A + B + 180^\circ$ and 50 the electrical difference between the limbs is $V = A - B + 180^\circ$.

In the network shown in Fig. 5 the difference $A - B$, may be quite small by making the difference 55 between points 26, 27, long in comparison with the spacing of the conductors of the transmission line 212. The longer the members A and B are made the smaller is the difference between their length, and consequently the closer is V to 180°. It can be readily seen that the current 60 along 212 which travels directly along path A will arrive at point 27, approximately 180° out of phase with respect to the current along path B and consequently will substantially neutralize 65 at this point. This effect of cancellation may be made absolute by making the length of arms A and B equal.

A more accurate arrangement of the X type short or network is illustrated in Fig. 3. In this 70 figure the insulator 35 is made quite long and thick and the conductors 23, 24, are drawn tight so that the whole network will assume the shape indicated in Figs. 4 and 5. Such an arrangement makes it possible for the limbs A and B to have 75 more nearly equal surge impedances and more

nearly equal lengths so that the theoretical conditions are more closely satisfied.

In practice it has been found that these refinements, such as shown in Figs. 3 to 5, are generally not necessary and that the arrangement such as shown in Fig. 2, in which the length between points 26 and 27 is equal to three or four times the spacing between the lines provides such excellent cut-off that it is usually good enough.

Although in the preferred form the cross connecting wires and the conductors between the points of connections are respectively of equal length it is evident that the lengths may be unequal if means are used to compensate for these inequalities.

The network when so constructed may be considered as serving to replace short circuiting bars. At some place in the network occurs a phenomenon which may be termed a virtual short, since it may be considered that if the network 20 were terminated by a perfect short circuiting bar at this point the same effect would occur, insofar as the external circuit is concerned. The position at which this virtual short occurs is usually very close to the center or crossing point of the 25 X. By the term virtual short is meant that point along the line at which a zero potential may be assumed in making calculations.

In order to more clearly explain this point reference is made to Fig. 6 in the drawings. In this figure a high frequency source 61 is connected to a transmission line T terminated into an X type short which produces a complete reflection of waves. The standing waves due to this reflection are indicated by the curve P. The position of the virtual short may be defined as the point (located in the X network) which is $\lambda/4$ from the nearest position of the current minimum. The position of this current minimum may be obtained from the table given below:

Table

$P_1 Q_1$	Distance from $P_1 P_2$ to first i min.	δ	Distance from $P_1 P_2$ to first i max.
Degrees	Degrees	Degrees	Degrees
5	87.5	2.5	177.5
10	85.0	5.0	175.0
15	82.5	7.5	172.5
20	80.0	10.0	170.0
30	74.0	16.0	164.0
40	67.0	23.0	157.0

This table represents calculations made in connection with a similar form of network, assuming that the difference V equals 180°.

From this table it may be seen that for X type shorts of usual dimensions the virtual short is located just beyond the crossing point of conductors 23, 24. In fact for the shorter lengths 60 the difference between the crossing point and the virtual short is so small as to render these points practically coincidental.

Experiments which have been made to check these conclusions agree very closely with the 65 table so that this table may be used as a guide for constructing such networks in most cases. When extreme precision is desired the exact position of the virtual short may be established by locating the voltage minimum point along the 70 transmission line and calculating the position of the virtual short from such measured positions from the known relations given above.

When speaking of virtual shorts it should be pointed out that the voltage between conductors 75

23, 24 at the point of virtual short is by no means zero. Likewise the voltage between the conductors of the transmission line section between the connection points of conductors 23, 5 24 is different from zero at this point. Both of these voltages depend upon the length of the conductors in terms of wavelengths. The point at which nearly zero voltage occurs across the line for the first time is the end of the X net- 10 work, that is, at points Q₁Q₂. This point is not really a point in the network at all since the voltage across the line remains nearly zero at all points beyond the X short. Furthermore this point has no significance such as for example, 15 the virtual short has, so that it is no more than the far terminal of the networks.

The network or X type short may be utilized in construction of metallic insulators, as shown in Fig. 7. In this arrangement the transmission line is supported and spread by means of the conductor section 72. Section 72 if provided with a complete short circuit at a distance a quarter of a wavelength below the transmission line which will have no effect upon the transmission 25 of waves along the line. Thus, if these wires are made of rigid material they may serve as an insulating spacer. In accordance with my invention a network or X type short as shown at 73 is provided, such that the virtual short of 30 the network is spaced at a distance equal to a quarter of a wavelength from the transmission line. With this arrangement the circuit 72 may serve as a spacing insulator, as well as a supporting insulator for the transmission line 212.

35 Similarly, the X type short may be utilized to replace the shorting bars in conjugate section arrangement, such as shown in Fig. 8. In such a conjugate arrangement the networks 82 may serve to introduce certain disturbances in the 40 line, and the network 83 may be so designed as to eliminate these disturbances, thus serving to cause a disturbance in the intermediate section of the line, which may be used to produce a suitable phase shift or other desirable changes 45 in the waves transmitted along the transmission line 212. By using the X type short in place of ordinary short circuiting bars, changes in the system due to any effect upon the conductors of networks 82, 83 at the points beyond the short 50 circuit and the other difficulties outlined above may be avoided.

In Fig. 9 a still further application of networks in accordance with my invention is disclosed. In this arrangement 91 represents a transmitting 55 antenna energized from source 92. Spaced from this antenna and insulated therefrom, is the parasitic reflector antenna 93. In order to obtain the proper effect of this parasitic reflector, the transmission line connected thereto may be 60 tuned by means of a network in accordance with my invention instead of an ordinary short circuiting bar. Such a network is shown at 94. Since the X type short or network substantially prevents any voltage developing in the wires 95 beyond this network, there is little danger of voltages developed in these wires causing a charring of the cross-arm 96. Furthermore, changes in the exact tuning of the reflectors 65 cannot be caused by changes in the wires 95 between the network 94 and the supporting cross-arm 96. Furthermore, it is immaterial 70 whether this section of wire 95 is close to a quarter wavelength of the frequency or not, since high voltages will not appear across the conductors and for this reason insulators are not neces- 75

sary between the conductor 95 and the bar 96. Where ordinary shorting bars are used high voltages may occur necessitating the use of other short circuiting bars. The use of an additional short circuiting bar will change the characteristics of the system requiring a complete retuning of the reflector. 5

A further application of a network or X type short, in accordance with my invention, is shown in connection with Fig. 10. It has been found 10 that when it is desirable to couple a high frequency source such as 100 or 101, with an antenna such as 102 or any other suitable load connected to a transmission line such as 103, that a substantial amount of coupling between 15 the line and auxiliary networks 104, 105 may be obtained by providing a short circuit or other suitable connection across the conductors 103 at a suitable point. This point should be so chosen that with respect to the particular wavelengths 20 used at 100 and 101, a high degree of coupling is had between the networks 104, 105 and the transmission line 103 at their respective frequencies, but substantially no coupling is obtained at other frequencies. In such an arrangement if an ordinary short circuiting bar is used the same difficulties arise as was manifested with respect to the supporting arrangement shown in Fig. 9. By utilizing an X type network 106 as shown in Fig. 10, these difficulties 30 are avoided and changes to the conductors between the network 106 and the supporting arrangement 107, is immaterial. In all these arrangements it should be remembered that the network should be so connected that the virtual 35 short occurs at the point ordinarily occupied by the shorting bars.

While I have disclosed the preferred form of network in accordance with my invention, together with a number of practical applications 40 thereof, these illustrations are intended to constitute merely a disclosure of my invention and not as limitations on the scope thereof. What I consider my invention and upon which I desire to obtain protection is defined in the appended 45 claims.

I claim:

1. A high frequency system comprising a two wire high frequency transmission line and means for producing a virtual short circuit between said conductors with respect to a particular frequency comprising two conductors of substantially equal length connected between said wires and crossing each other the lengths of said conductors and their positions relative to one another along said wires being such that the portions of said transmission line between points of connection is substantially equal to the length of either of said conductors to produce a virtual short circuit for said particular frequency across said transmission line at a point other than those at which said conductors are connected. 50 55 60

2. A high frequency network comprising a pair of spaced conductors, and a pair of diagonally arranged conductors of substantially equal length crossing substantially at their centers and insulated from each other connected between said spaced conductors the points of connection of said diagonally arranged conductors being separated by a distance equal to at least three times 65 70 the spacing between said spaced conductors.

3. A high frequency network for use in a two conductor transmission line, comprising a pair of substantially straight crossed conductors insulated from one another and connected between 75

the conductors of said transmission line at spaced points, and the section of transmission line between said spaced points, separated by a distance equal to at least three times the separation of the two conductors of said transmission line.

4. A high frequency system comprising a transmission line connected to means for producing high frequency standing waves on said line, and a network for producing a zero potential in the line at points beyond said network, comprising a pair of substantially straight, equal length crossed conductors connected across said transmission line at a point determined by said standing wave minimum, said network including a portion of said transmission line substantially equal in length to said conductors to produce a virtual short at a point a quarter wavelength from said minimum.

5. A high frequency network comprising a first pair of conductors of equal length arranged in lateral spaced relation with one another, and a second pair of conductors of equal length and of substantially the same length as said first pair of conductors insulated from one another, arranged in crossed relationship with respect to one another and connected between the ends of said first conductor pair, the said lengths being at least three times the said lateral spacing.

6. A high frequency network comprising a first pair of conductors of equal length arranged in lateral spaced relation with one another, a second pair of conductors of equal length and of substantially the same length as said first pair of

conductors arranged in crossed relationship with respect to one another and connected between the ends of said first conductor pair, and insulating means serving to maintain separation of said first pair of conductors and to insulate said second pair of conductors from each other at their point of crossing, said conductor length being at least three times said lateral spacing.

7. A high frequency system comprising a two conductor transmission line for waves of a particular high frequency, and means for producing a virtual short circuit with respect to said frequency comprising a pair of crossed conductors of substantially equal length connected between said transmission line conductors at points spaced apart a distance at least three times the separation of said line conductors to establish a virtual short circuit at a distance a quarter wavelength of said frequency from a standing wave minimum in said line.

8. An isolating support for a two wire high frequency transmission line, comprising a pair of spaced conductors connected respectively to the separate conductors of said line, a pair of substantially equal length crossed conductors connected at their ends to the conductors of said pair, said crossed conductors being long relative the spacing of said conductors, said crossed conductors crossing each other at a point slightly less than a quarter wavelength of said high frequency from said high frequency line.

ANDREW ALFORD.
